UNITED STATES PATENT OFFICE

WILLARD A. ORMSBEE, OF TAUNTON, MASSACHUSETTS

DESIGN FOR A SUSPENDER BUCKLE

Application filed December 27, 1928. Serial No. 29,420. Term of patent 3½ years.

To all whom it may concern:

Be it known that I, WILLARD A. ORMSBEE, is a citizen of the United States of America, residing at Taunton, county of Bristol, State of Massachusetts, have invented a new, original, and ornamental Design for a Suspender Buckle, of which the following is a specification, reference being had to the accompanying drawing, forming a part thereof.

I claim:

The ornamental design for a suspender buckle, substantially as shown.

WILLARD A. ORMSBEE.
